UNITED STATES PATENT OFFICE.

WINFRED A. BROWN, OF MINNEAPOLIS, MINNESOTA.

BROOM.

Application filed October 8, 1925. Serial No. 61,286.

The invention aims to provide a simple and inexpensive broom which is especially adapted for sweeping under seats in schools, theaters, and the like, or beneath radiators or other objects under which sweeping cannot be effectively accomplished with the ordinary brooms.

The improved broom includes a horizontally elongated brush and an inclined handle extending from the back thereof, further objects being to provide unique means for adjustably connecting the handle with the back, and to provide for reversal of the handle when one end of the brush has become worn, so that the other end will then receive the greater part of the wear.

With the foregoing and minor objects in view, the invention resides in the novel subject matter hereinafter described and claimed, the description being supplemented by the accompanying drawing.

Figure 1 is a top plan view partly in section.

Figure 2 is a longitudinal sectional view on line 2—2 of Fig. 1, showing the handle in its reversed position in dotted lines.

Figure 3 is a detail side elevation showing the handle in one of its numerous adjustments.

Figure 4 is a transverse sectional view on line 4—4 of Fig. 2.

Figure 5 is a view similar to Fig. 4 but showing a slightly different form of construction.

The numeral 6 designates a horizontally elongated brush back from which bristles 7 extend, the upper side of said back being either flat as disclosed in Fig. 4 or arched as illustrated in Fig. 5.

Contacting with the upper side of the back 6 and transversely shaped to conform to the shape of the upper side of said back, is a horizontally elongated metal plate 8 having an inclined socket 9 near one end to receive an inclined handle 10. This end of the plate 8 is formed with an opening 11, and a longitudinal slot 12 extends from a point near the other end of said plate, to a point near the lower end of the socket 9.

A screw or other suitable fastener 13 passes through the slot 12 and in the present disclosure is located at the center of the back

6, so that upon loosening of this screw and removal of another screw or the like 14 which passes through the opening 11, the 55 plate 8 may either be reversed to the dotted line position shown in Fig. 2 or may be longitudinally adjusted upon the back 6, for instance, from the position of Fig. 2 to that disclosed in Fig. 3. After reversal or adjustment, or both, of the plate with respect to the back 6, the screw 14 is passed again through the opening 11 and engaged with the brush back, and the screw 13 is again tightened, so that the plate and back will 65 be rigidly connected to effectively connect the handle 10 with the brush.

Preferably, each end portion of the brush back 6, is formed with a plurality of openings 15, spaced apart longitudinally of said back, any of these openings being adapted to receive the screw or the like 14.

It will be seen from the foregoing that a broom has been provided which is simple and inexpensive and is well adapted for sweeping beneath objects, at points which cannot be easily reached with the ordinary brush or broom. It will also be seen that the handle may be adjusted with respect to the brush to suit the conditions under which the device must be used, and that whenever the one end of the brush becomes noticeably worn, the handle may be reversed, causing the other end of said brush to receive the greater amount of wear. Thus, the brush 85 will last a great deal longer than would otherwise be possible, and it cannot get so seriously out of shape as to be inefficient.

As excellent results have been obtained from the details disclosed, they are by preference followed. However, within the scope of the invention as claimed, modifications may be made.

I claim:—

In a broom, a brush having a horizontally elongated back, an elongated plate resting on the upper side and extending lengthwise of said back, said plate having an inclined handle near one end and an opening in said one end, said plate being of a length slightly more than one-half that of the brush back and having a longitudinal slot from its inner end to the handle, a fastener passing through said slot and engaged

with the medial portion of the back to pivotally and longitudinally slidably mount the plate for adjustment lengthwise of the back of the brush, said back having openings spaced longitudinally from opposite sides of the fastener, and a second fastener passing through the first named opening for selective reception in the spaced openings to

permit securing of the handle at either end or the center of the back whereby one end of the brush will project a considerable distance beyond the point of connection of the handle with the plates. ¹⁰

In testimony whereof I have hereunto affixed my signature.

WINFRED A. BROWN.
